ROTARY RADIAL PISTON PUMP

John B. Hawley, Jr., Minneapolis, Minn., assignor
to Reconstruction Finance Corporation, Minne-
apolis, Minn., a corporation of the United States

Application August 28, 1936, Serial No. 98,300

6 Claims. (Cl. 103—161)

This invention relates to a liquid pump of the rotary piston type. Such pumps are now largely used for furnishing liquid, such as oil under pressure, for the operation of hydraulic presses, motors and other machines operated by a liquid such as oil under pressure.

It is an object of this invention to provide such a rotary pump of high durability and efficiency. This requires very accurate construction and arrangement of the parts so that a minimum of wear is had.

It is another object of the invention to provide a rotary radial piston pump in which the pistons are reciprocated by forces acting in a direct radial line so that there is no tendency to move the pistons laterally against the cylinder wall.

It is a further object of the invention to provide a rotary pump of the piston type in which the pistons reciprocate in cylinders formed in a rotating cylinder block, said pistons being carried on cross heads guided in said block and having rollers thereon engaging with the inner side of a rotating ring provided with a full floating mounting.

It is still another object of the invention to provide a rotary pump of the piston type comprising a pintle flexibly supported at one end and having roller bearings spaced longitudinally thereof to maintain said pintle concentric with said block, said cylinder block also rotating on roller bearings carried in the housing of said pump.

It is still another object of the invention to provide such a pump as set forth in the preceding paragraph in which the said pintle is provided with spaced passages extending longitudinally thereof, through which the liquid enters and is discharged respectively, said passages having ports communicating with ports leading into the cylinders formed in said cylinder block, said block having cylinders spaced longitudinally thereof and having a common port communicating with said ports in said pintle.

It is another object of the invention to provide a rotary pump of the radial piston type having a stationary pintle and a cylinder block rotatable thereabout, said block running on spaced bearings carried on said pintle and being spaced very slightly from said pintle between said bearings together with means for forcing oil through said pintle and about said pintle between said bearings to lubricate said pintle and bearings.

It is another object of the invention to provide a rotary pump of the radial piston type comprising a housing, a pintle supported at one

end and extending into said housing, a cylinder block rotatable about said pintle on bearings disposed about said pintle and also on bearings supported in said housing, said cylinder block having radial cylinders formed therein, pistons reciprocable in said cylinders having roller-carrying means secured thereto, a ring rotatable about said cylinder block on bearings carried in said housing and means for positively lubricating all of said bearings.

It is another object of the invention to provide a rotary pump of the radial piston type comprising a pintle flexibly secured at one end, a housing into which said pintle extends, a cylinder block rotatable about said pintle on roller bearings carried by said pintle and spaced longitudinally thereof and on bearings carried by said housing of greater diameter than said first mentioned bearings and adjacent the fixed end of said pintle together with means for permitting flexing of said pintle laterally in said last mentioned bearings to permit said bearings to maintain a concentric position.

These and other objects and advantages of the invention will be fully set forth in the following description made in connection with the accompanying drawings, in which like reference characters refer to similar parts throughout the several views and in which:

Fig. 1 is a view partly in side elevation and partly in vertical section taken substantially on line 1—1 of Fig. 3.

Fig. 2 is a view partly in side elevation and partly in vertical section taken substantially on line 2—2 of Fig. 3;

Fig. 3 is a vertical section taken substantially on line 3—3 of Fig. 1, all of said sections being taken as indicated by the arrows;

Fig. 4 is a view in side elevation of the pintle used, a part being broken away and another part shown in vertical section;

Fig. 5 is a vertical section taken on line 5—5 of Fig. 4 as indicated by the arrows;

Fig. 6 is a view partly in side elevation and partly in vertical section of a piston assembly;

Fig. 7 is a bottom plan view of the parts shown in Fig. 6 or as seen from line 7—7 looking in the direction of the arrows;

Fig. 8 is a view similar to Fig. 2 showing a modification;

Fig. 9 is a view similar to Fig. 7 showing a different construction;

Fig. 10 is a view partly in side elevation and partly in vertical section of the parts shown in Fig. 9; and

Fig. 11 is a view in side elevation of the piston assembly shown in Figs. 9 and 10.

Referring to the drawings, a pump of the rotary radial piston type is shown comprising a housing or casing 10. This housing has a suitable base portion 10a provided at corners with apertures 10b adapted to receive foundation bolts. Said housing 10 is roughly rectangular in shape with rounded corners at its upper side and is provided with suitable strengthening ribs 10c. A front cover or bearing plate 11 is secured to one side of housing 10 by the headed cap screws 12. Cover 11 is provided with holes 11a to give access to the housing and said holes are covered by plates 11b bolted to plate 11. A rear cover or bearing plate 13 is also provided and secured to the side of the housing by bolts 13a. A suction or inlet member or nozzle 14 is provided, the same having a flange 14a bolted to the rear cover 13 by the screws 15, said screws passing through the holes 14b in flange 14a. Member 14 has an inlet opening or bore 14c and a pipe 16 extends from member 14 and bore 14c to an adapter member 17, pipe 16 being very rigidly secured to both members 14 and 17. A discharge member or nozzle 18 has a flange 18a secured to rear cover 13 at the side opposite that to which member 15 is secured, member 18 being secured by screws 19 passing through the holes 18b. Member 18 has a discharge outlet or bore 18c and a discharge pipe 20 is rigidly secured to member 18 and communicates with bore 18c, said pipe extending to and being rigidly secured at its other end to an adapter member 21. Members 17 and 21 are similar in construction but reversely arranged and the same have passages 17a and 21a formed therein with which pipes 16 and 20 communicate and which they align respectively. A pintle member 22 is disposed between members 17 and 21 and is rigidly clamped therebetween by the headed and nutted bolts 23 passing at each side of said pintle. Pintle member 22 has annular slots or grooves 22a arranged in the sides thereof and members 17 and 21 have ribs 17b and 21b formed thereon fitting in said slots 22a. Gasket members 17c are disposed in the bottom of slots 22a and are engaged by the tops of the annular ribs 17b and 21b. Pintle member 22 extends through the rear cover 13 and into the housing 10. A cover plate 24 has an opening through which pintle 22 passes, said cover being secured to the rear cover 13 by bolts 25. As shown in Fig. 2 the portion of pintle 22 disposed between members 17 and 21 is substantially rectangular in cross section. The portion of the pintle projecting beyond members 17 and 21 is cylindrical. Plate 24 has a recess 24a at its outer side adjacent pintle 22 and the portion adjacent said pintle as shown in Fig. 3 is rectangular in radial cross section. A leather washer or ring 27 of angle shape in cross section extends around said recess with its angle directed inwardly and a ring 28 of cork or similar material fits in said washer and recess. A plate 30 is secured to the outer side of plate 24 by the countersunk screws 31, which plate extends over the recess 24a and is slightly spaced from the pintle 22. Washer 27 engages pintle 22 and forms a seal with plates 24 and 30.

70 A cylinder block 32 is provided which rotates about pintle 22 concentric therewith. Block 32 runs about roller bearings 33 of great accuracy and hardness carried on pintle 22 adjacent the fixed end of the latter and about another set of similar rear bearings 34 carried at the reduced

end 22b of pintle member 22. A cap plate 35 is secured to the inner end of pintle 22 by the circumferentially spaced screws 35a and is centrally bored and threaded to receive a plug 36. Pintle 22 is provided with a comparatively small axial bore 22c which is enlarged at its outer end to receive a lubricating connection 37. Oil passages 22cc extend from bore 22c to the cylindrical surface of pintle 22 between bearings 33 and 34. Between bearings 33 and 34 the cylinder block is very accurately bored to have a very small clearance about pintle 22. In practice this clearance varies from one to five thousandths according to the diameter of the pintle. A snap ring 39 extends about pintle 22 adjacent bearing 33, said pintle at this point being of slightly smaller diameter than its diameter within the inner shell of bearing 33. Pintle 22 has a plurality of inlet and outlet passages 22d extending longitudinally thereof. The inlet passages communicate with opening 11a while the outlet passages communicate with opening 21a. At the inner portion of the pintle substantially centrally between the bearings 33 and 34 the pintle has openings or ports 22e extending to its periphery from the passages 22d. Pintle 22 between the ring 39 and its reduced portion 22b is provided with a shell 22f of some bearing metal or anti-friction metal, such as bronze, said shell being firmly secured to said pintle. Said pintle at each side of the ports 22e and at equal distances therefrom is provided with narrow grooves 22g of substantially the same circumferential extent as the openings or ports 22e. Said grooves are connected by drilled holes to the inlet and outlet ports 35 respectively on the opposite side of the pintle. These are provided to equalize the pressure radially or transversely of pintle 22.

The cylinder block 32 is provided with a plurality of radial bores 32a, forming cylinders, and these bores have openings or ports 32b at their lower ends at the inner side of the block adjacent the pintle 22 which align with the ports 22e as shown in Fig. 3. Block 32 at the outer side of each bore or cylinder 32a has a slot with parallel sides and of substantially the same width as the diameter of the cylinder bore. Cross heads 40 are movable radially in said slots and carry roller bearings 41 in which is journaled the cross head roller or pin 42. The cross heads 40 have secured thereto the pistons 43. Each piston comprises a shell 43a of brass or similar metal through which extends the cylindrical portion 40a of the cross head 40, the lower reduced and threaded end 40b of which receives the securing nut 44. Nut 44 is provided with a plurality of chamfered slots 44a for the application of a tightening tool. Portion 40a is provided with a plurality of annular grooves 40c adapted to receive oil. It will be noted that the lower end of shell 43a is quite thin and that there is a space between its inner side and the nut 44. Pin 42 has an integral enlargement or collar 42a thereon at its central portion between the cross heads 40 and said pin has secured at each outer end 65 adjacent cross heads 40 the rollers 45. The cylinder block 32 also rotates on roller bearings 46 mounted respectively in the front and rear cover plates 11 and 13. A bearing lock plate 47 is secured to the front end of member 32 by the bolts 70 48, the same engaging the outer side of front bearings 46. A locking plate 49 is also secured to the rear end of member 32 by bolts 50 and engages the outer side of rear bearing 46. Plate 49 also engages the end of a spacer bushing 51, 75

the inner end of which engages the bearing 33. Member 32 is bored at its front end to receive the enlarged inner end 52a of the drive shaft 52 to which it is secured by the two keys 53. Drive shaft 52 is also provided with a flange 52b and is further secured to member 32 by the screws 55 passing through flange 52b into member 32. Passages 52c extend through portion 52a and flange 52b for lubrication purposes. The drive shaft 52 extends outwardly through an end cover member 54 having a flange secured to the front housing cover 11 by the circumferentially spaced screws 55. Cover plate 54 also has an inner flange 54a engaging the outer side of front bearing 46. Plate 54 also has a recess in its outer side which forms about shaft 52 a recess rectangular in radial cross section. A washer or ring 54c of leather or similar material is disposed in said recess, the same being of angle shape in cross section and having its angle directed inwardly. A ring 54d of cork or similar material is disposed within the angle of washer 54c and fills the remainder of said recess. Members 54c and 54d thus form with plate 54 a yielding seal about shaft 52. An end cover plate 54e is secured to an annular outwardly projecting flange on plate 54, the inner edge of which is spaced slightly from shaft 52.

The rollers 45 and the collar 42a engage at their outer sides a ring 56 which rotates and has a floating mounting on roller bearings. Ring 56 has secured to each side thereof by screws 59 the annular side plates 57 and 58 having cylindrical portions through which the cylindrical end portions of the cylinder block extend. Plates 57 and 58 are carried on the roller bearings 60 also carried in a ring or rotor guide member 61. Plates 57 and 58 have oil passages 57a and 58a formed respectively therethrough. The rotor guide member 61 has a slot 61a extending transversely thereof at its bottom and shafts or pins 62 extend across this slot having mounted thereon rollers 63 carried on roller bearings 64 surrounding the shafts 62. The rollers 63 roll upon the flat surface of a hardened plate 65 secured by screws 66 to a larger plate 67 mounted on the housing 10. Said roller guide 61 has a similar slot 61b at its top across which extend the shafts 68 having mounted thereon rollers 69 similar to rollers 63 and also mounted on roller bearings 70 surrounding the shafts 68. The rollers 69 engage the flat under surface of a hardened plate 70 also secured in any suitable manner to the top of housing 10a. The member 61 also has slots 61c adjacent its top and bottom and at either side thereof, across which extend the pins or shafts 71 on which are mounted rollers 72, said rollers being mounted on roller bearings 73 surrounding the pins or shafts 71. The rollers 72 engage against the flat vertical surface of a plate 74, there being such a plate at each side of member 61, said plates being suitably secured to the housing 10. Member 61 has secured thereto a plate 75 having projecting lugs 75a in which is secured a pin or shaft 76, held in place by the pins or keys 77 extending therethrough at the outer sides of lugs 75a. Pin 76 extends through a member 78 which is thus connected to member 75 and member 78 has projecting spaced lugs 78a through which extends a pin or shaft 79 held in place by pins or keys 80 extending therethrough adjacent its ends and at the outer sides of lugs 78a. Members 75, 78 and attached parts are provided to form a connection to the means which moves the rotor guide 61. This movement in the pumps is sometimes done manually and at

other times is done by automatic control means.

In Fig. 8 a modified form of connection for the nozzles and pintle is shown. The intake member or nozzle 85 corresponding to member 14 is shown, the same having the intake opening 85a, the attaching flange 85b with holes 85c therethrough as well as the flange 85d adapted to engage the housing and to which it will be connected by bolts passing through the holes 85e. Member 85 is connected to an adapter member 86 by a pipe 89 which is of U-shape. Pipe 89 thus has two right angle bends therein and its ends will be securely and rigidly fastened to members 85 and 86. Pipe 89 will, of course, communicate with the bore 85a and at its other end communicates with the bore 86a of member 86. A discharge member 87 similar to member 85 is provided, the same also having a bore 87a, the flange 87b with holes 87c therethrough and the attaching flange 87d provided with the holes 87e adapted to receive attaching bolts. Member 87 is connected to an adapter member 88 similar to member 86 by pipe 89a, which pipe is also of U-shape and similar to pipe 89. Pipe 89a will be firmly connected at its ends to members 87 and 88 and communicates with bore 87a and the bore or passage 88a in member 88. A pintle member 90 is provided having a portion rectangular in cross section disposed between members 86 and 88, the same having annular grooves 90a formed in its opposite sides into which project the ribs 86b and 88b formed on members 86 and 88 respectively. Gaskets 91 are disposed in the bottoms of grooves 90a and members 86 and 88 are drawn firmly against these gaskets by cap screws 92 passing through members 86 and 88 and into pintle member 90. Pintle member 90 is provided with inlet passages 90b, discharge passages 90c and a central lubricating passage 90d as already described in connection with pintle 22.

Pintle 90 like pintle 22 is connected to the adapter members at each side thereof by tension members which are somewhat elastic. With the construction shown in Fig. 2 the nozzle members are rigid with the adapter members in a direction at right angles to the bolts 23. In the construction shown in Fig. 8 there will be some elasticity or flexibility in the connection between the nozzle members and the adapters. The pipes 89 and 89a due to their U-shape will have some give or elasticity and a more flexible construction is thus provided. Separate cap screws are also used instead of the continuous bolts 23.

In Figs. 9, 10 and 11 another construction of the piston assembly is shown. A cylinder block 95 is shown, which block is provided with only one cylinder 95a longitudinally thereof. There will, of course, be a plurality of these cylinders circumferentially of the block. In the pumps having just the one cylinder longitudinally of the cylinder block the cross head 96 which reciprocates in a bore 95b in the block is of cylindrical form. Said cross head has the inwardly extending reduced portion 96a forming the piston core about which extends the shell or sleeve 97 of the piston, the same being counterbored at its inner end to receive the holding nut 98 threaded on a reduced portion of core 96a and being disposed in the inner end of the shell 97. Cylinder 95a has a port 95c for the passage of oil from and into the pintle. Cross head 96 has extending transversely thereof and supported on roller bearings 99 therein, the pin 100. Pin 100 has secured to its ends at each side of block 95 the roller 101 which as already described will run against the

inner side of the ring which moves the cross heads and pistons. The bore for cross head 96 as shown in Fig. 1 is considerably larger than the cylinder bore and the diameter of this bore is 5 somewhat larger than the width of the cylinder block. A keyway 96b is formed in one side of cross head 96 in which is disposed a key member 102 secured in cylinder block 95 by the pin 103. The core member 96a is also provided 10 with a plurality of annular grooves 96c.

In the pumps having more than one cylinder lengthwise of the cylinder block the cross heads 40 as shown in Figs. 1 and 3 are rectangular in cross section and with this construction 15 and with more than one cylinder there can be no movement of pin 42 about a radial axis extending centrally therethrough. It has been found, however, that in the pumps having just one cylinder in the cylinder block where the cross head is cylindrical in cross section that the cross head pin will rotate about a radial axis of the cylinder block which would also be the central axis of the cross head. This causes the rollers 101 to engage the sides of the cylinder block and 20 also to engage the sides of the members carrying the rotating ring. To prevent this rotation the key 102 is provided. The cross head reciprocates and this key slides in the keyway or spline 96b so that any rotary movement of cross head 96 25 is prevented.

In operation, liquid, which is customarily oil, is supplied to intake member 14c. Shaft 52 is rotated, thus rotating a cylinder block 32. Ring 56 is likewise rotated by the component forces 30 of rollers 42a and 45a. When ring 56 is in position concentric with the pintle 22 the rollers 45 travel thereabout and there is no movement of the pistons radially of the cylinders in the cylinder block. Ring 56 can be moved to the 35 right or left as seen in Fig. 1 by movement of the ring or rotor guide member 61. This is accomplished either manually or automatically by means not shown. When ring 56 is moved to position eccentric with the pintle 22 there will be 40 an inward movement of the pistons at one side of the ring and an outward movement of the pistons at the other side of the ring. The rollers 45 will remain in contact with ring 56 and at the side where the ring is closest to the cylinder 45 block they will be pushed inwardly and will move outwardly against the ring by centrifugal force at the other side. As the pistons 43 move outwardly they exert suction and the oil is drawn through pipe 16, through the adapter member 17 and through the inlet passages of the pintle, 50 then out through the ports 22c into the cylinders. As the pistons move around and are pushed inwardly this oil is forced out through the outlet or exhaust ports of the pintle, into the exhaust passages, out through member 21 and pipe 20 and through the discharge member 18. The stroke of the pistons can be regulated or adjusted by movement of the ring 56, which, as stated, 55 is accomplished by moving member 61. The member 61 and parts carried thereby has considerable mass or weight and thus has considerable inertia. It is important that in the operation of the pump this member and ring 56 be 60 very easily moved. When the pump is part of a control system, such as a system used for steering a battleship, slight movements of the ring are necessary. For this reason the rollers 63 and 72 are provided so that rotor guide 61 can be moved with a very small force and is thus very easily 65 controlled.

As stated, there is a small space between the cylindrical portion of the pintle between bearings 33 and 34 and there is usually a film of oil between these parts. The cylinder block runs on the bearings 33 and 34. When the pump is operating 5 with ring 56 out of the concentric position there is high pressure on the oil and the oil film on the pintle can be maintained without difficulty. If the pump is not operating under pressure the lubrication of the pintle may not be maintained. 10 In order to overcome this difficulty the bore 22c is provided and oil is forced through this bore from connection 37 by some suitable oil circulating means and this oil is forced out through the passages 22cc to insure that the pintle will be 15 properly lubricated. To further insure a proper bearing should any friction occur between the rotating cylinder block and said portion of the pintle the shell 22f is provided. This will insure that there will be a proper bearing between the 20 materials of the cylinder block and shell should the cylinder block for any reason rub against the pintle. The pintle may possibly be deflected by the high pressures or the difference between 25 the suction and discharge temperatures causing thermostatic action to cause such contact. The grooves 22g are provided to equalize the radial pressure on the pintle.

The grooves 40c are provided within the piston shells to prevent air being forced by suction 30 along the inner sides of the piston shells 43a. The grooves 40c fill with oil and passage of air is thus prevented.

The shells or piston sleeves 43a also are made of material having a coefficient of expansion 35 greater than the coefficient of expansion of the material of the cylinder block. When the pump is operating the oil becomes heated under the high pressure and the pistons thus also become heated. The pistons will expand, however, and 40 maintain a good seal in the cylinders due to their greater coefficient of expansion. The lower ends of the pistons as stated have rather thin walls and the high pressure of oil against or within the ends of the pistons will expand the inner 45 end of the piston somewhat, causing it to maintain a closer fit in the cylinder. The collar or roller 42a being integral with the pin 42 prevents any end slip of this pin. The lubrication of the bearings is assured by the forced feed of oil 50 through bore 22c of the pintle as well as by the flow of oil caused by the pressure. The oil forced through the passages 22c will pass to the outer end of the pintle into the bearings 34. Any oil forced between the pintle and cylinder block will 55 also pass out through the bearings 34. The oil will pass into the opening at the end of the pintle and between the same and the drive shaft. The oil will pass through the passages 52c, into the space inside of cover plate 54 and through 60 bearings 46. Oil will also pass from the cylinders out along the rollers 45, through the passages 57a and 58a and through the bearings 60 so that all of these parts will be positively lubricated. Oil will also pass from around the pintle between 65 bearings 33 and 34 toward the larger end of the pintle, through the bearings 33, into the space between bushing 51 and the pintle, into the space within plate 24 and through the bearings 46. These bearings will thus be positively lubricated. 70 The oil after passing through the various bearings passes to the bottom of the housing which forms a sump and is provided with a suitable drain.

By having the cylinders arranged longitudinally in pairs and closely adjacent as shown in 75

Fig. 3, it is possible to have a common port leading from the cylinders to the pintle. This is an important part of the construction as it enables the bearings 33 and 34 to be brought closer together which insures that the cylinder block and pintle will rotate more readily in concentric relation. Due to the high pressures used there is a tendency to deflect the pintle which is of cantilever construction. It will be noted that the cylinder block runs about bearings which are concentrically arranged and that one set of bearings is within a smaller radius or circumference than the other. Thus bearings 34 are smallest, being on the small end of the pintle, bearings 33 are somewhat larger while the bearings 46 on which the cylinder block also runs are of considerably greater diameter. It is a very difficult task and one almost impossible to mechanically construct such bearings so that they will at all times be in perfect concentric relation. There can be more variance provided for in the larger bearings than in the smaller bearings. In order to insure that the bearings 33 and 34 will be maintained concentric with the pintle the yielding construction formed by the leather washers 27 and 54c and the cork rings 28 and 54d is provided. Should the pintle be deflected by the pressure or for any other reason bearings 33 and 34 will continue to be concentric with the pintle and the pintle can shift laterally a short distance adjacent its supported end and the variation will be made in the bearings 46 which can more easily stand a slight variation. The movement, of course, will be exceedingly small. Were the bearings at the fixed end of the pintle rigid the bearings 33 and 34 would have to gyrate or run out of true and this would produce a wedging action on these bearings. At the high speeds and pressures used the mechanical problems presented are, as stated, quite difficult. The oil taken into the pump is usually at considerably lower temperature than the oil at the discharge side which is raised in temperature by the work producing the pressure and friction. This difference in temperature at the sides of the pintle is one factor tending to deflect the pintle by thermostatic action.

From the above description it is seen that applicant has provided a pump of the rotary radial piston type which will operate with great efficiency and accuracy. The various problems encountered in the construction of such a pump have been solved by the construction and arrangement above described. The pump has been amply demonstrated in actual practice, found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:

1. A pump of the rotary radial piston type having in combination, a pintle having a portion

integral therewith having substantially parallel sides, spaced intake and spaced discharge passages extending longitudinally of said pintle, said pintle having an opening through one of said parallel sides communicating with said intake passage and having an opening through the other or said parallel sides communicating with said discharge passage, annular grooves in said sides about each of said openings, intake and outlet members having openings therein with annular ribs thereabout fitting respectively in said grooves and means for clamping said intake and outlet members to said pintle whereby said pintle may have flexing movement about the axis of said grooves.

2. The structure set forth in claim 1, said last mentioned means comprising tensioned members extending through said intake and outlet members and at opposite sides of said pintle.

3. A pump of the rotary radial piston type having a pintle flexibly supported only at one end, a cylinder block rotatable about said pintle and running about bearings spaced longitudinally of said pintle and carried thereby, a housing, said cylinder block also running on a bearing in said housing adjacent the supported end of said pintle, said last mentioned bearing being of larger diameter than said first mentioned bearings, said cylinder block being movable a short distance relatively to said pintle transversely thereof adjacent the supported end of the latter.

4. A pump of the rotary piston type having in combination, a housing, a pintle having inlet and outlet passages leading therefrom, members rigidly secured to said housing, curved pipes connected respectively to said members, members disposed at either side of said pintle for supporting one end thereof and having passages communicating respectively with said inlet and discharge passages, means for clamping said last mentioned members to said pintle for supporting said pintle, said curved pipes being connected at the other ends respectively to said first mentioned members.

5. A pump of the rotary piston type having in combination, a housing, a pintle having a portion with inlet and outlet passages, members at either side of said pintle having passages communicating respectively with said passages, means for clamping said pintle between said members, said members having provision for slight movement in planes respectively parallel to the axis of said pintle, members rigidly secured to said housing at opposite sides of said pintle, and conduits connecting said first mentioned members and last mentioned members constructed and arranged to permit movement in a direction at right angles to said first mentioned movement.

6. A pump of the rotary piston type having in combination, a housing, a pintle having inlet and discharge passages leading therefrom, members at opposite sides of said pintle having passages communicating with said passages, means for securing said members and pintle together, inlet and discharge members secured to said housing, and conduits having U-shaped bends respectively securing said last mentioned members and said first mentioned members.

JOHN B. HAWLEY, JR.
